The ornamental design for a bi-fold roofing material display, as shown and described.

DESCRIPTION

FIG. 1 is a top perspective view of a bi-fold roofing material display in a closed position, showing my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of a bi-fold roofing material display in an open position;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The stippling in FIGS. 5-9 and 11-14 represents a contrast in appearance.

1 Claim, 10 Drawing Sheets(56)
